UNITED STATES PATENT OFFICE.

HARRY D. CESSNA, OF SAN FRANCISCO, CALIFORNIA.

ELECTRIC FAN.

No. 829,819.

Specification of Letters Patent.

Patented Aug. 21, 1906.

Application filed April 27, 1905. Serial No. 257,619.

To all whom it may concern:

Be it known that I, HARRY D. CESSNA, a citizen of the United States, and a resident of San Francisco, in the county of San Francisco and State of California, have invented a new and Improved Electric Fan, of which the following is a full, clear, and exact description.

My invention relates to fans, my more particular object being to produce a type of fan driven by a motor and capable of shifting bodily from one point to another while in action.

My invention also relates to certain constructional details for improving the efficiency of the fan and for enabling it to be moved automatically; as hereinafter described, and pointed out in the claims.

Reference is to be had to the accompanying drawings, forming a part of this specification, in which similar characters of reference indicate corresponding parts in all the figures.

Figure 1 is a horizontal section through the carriage upon which the revolute fan members are mounted and also containing the electric motor mechanism and related parts for actuating and controlling the fan members, the section being taken upon the line 1-1 of Fig. 4 looking in the direction of the arrow. Fig. 2 is a vertical cross-section through the aforesaid carriage, showing the track mechanism and the trolley mechanism, together with the mountings for the motor and also the mountings for some of the fan members, the section being taken upon the line 2-2 of Fig. 4 looking in the direction of the arrow. Fig. 3 is a vertical cross-section through the carriage and is taken upon the line 3-3 of Fig. 4 looking in the direction of the arrow and showing the clutch mechanism for reversing the direction of travel of the carriage and also showing the means for operating this clutch mechanism. Fig. 4 is a reduced side elevation of the track, showing the carriage as depending therefrom and also showing the means for suspending the track from the ceiling which appears in section; and Fig. 5 is a diagram of the wiring.

The ceiling is shown at 5, and depending from it, preferably upon opposite sides of the room, are brackets 6 7. From one of these brackets to the other a line 8 is suspended, as indicated in Fig. 4. Suspender-straps 9 are each provided with an eye 10, which encircles the line 8, and mounted upon the suspender-straps 9 is a track 11, provided at one of its ends with a cam-plate 11^a, this plate

being upon one side only of the track, and upon the opposite side (but at the other end) of the track is another cam-plate 11^b, as indicated in Figs. 3 and 4. The bottom of each suspender-strap 9 is threaded at 12 and supports a stirrup 13, through which passes a pin 14. Metallic plates 16 17 are provided with upwardly-projecting flanges 15, which are supported by the several pins 14, passing therethrough, as indicated in Fig. 2. The plates 16 17 are bent upwardly at 18 19, so as to constitute track-rails and are held in position by screws 20 21. Trolley-conductors 22 23, insulated by means of an asbestos or fiber plate 24, are mounted upon the under side of the rail 11, as indicated in Fig. 2. A carriage 25 is provided with an upwardly-projecting neck 26 of considerable size and is provided for the protection and concealment of the several working parts. Connected rigidly with the carriage 25 are bearing-sleeves 27 28, supporting bevel-gears 29 30, mounted, respectively, upon revolute shafts 31 32, these shafts being provided with fan members 33 34. The bearing-sleeves 27 28 are provided with upwardly-projecting lugs 35, and bolted rigidly to these lugs are supporting-strips 36, which are secured rigidly to the electric motor 37 and support the same within the carriage.

Mounted rigidly upon the motor 37 and extending upwardly therefrom are standards 38 39, and revolutely mounted upon the upper ends of these standards are track-wheels 40 41, which rest upon the rails 18 19 of the track 11 and partially support the carriage. Bearing-sleeves 42 are connected rigidly with the motor and support a fan member 43, which, together with a bevel-gear 44, is rigidly mounted upon a shaft 45, and therefore free to turn therewith. Another fan member 43^a is mounted upon the shaft 45 directly opposite the fan member 43, as indicated in Fig. 1. Projecting obliquely upward from the motor 37 are trolleys 46 47, each provided with a trolley-wheel 46^a 47^a, as indicated in Fig. 2. The trolley-wheels make contact with the respective trolley-conductors 22 23, which may be regarded as miniature "third rails" and are employed for the purpose of supplying current to the electric motor 37, as hereinafter described.

At the right of the carriage, according to the view shown in Fig. 3, a pair of track-wheels 48 49 are respectively provided with bevel-gears 50 51, preferably integral there-

with, as shown. Each bevel-gear is revolvably mounted upon a stub-shaft 52, supported by a sleeve 53 and projecting laterally therefrom, there being two of these sleeves, as indicated in Fig. 3. The bevel-gears 50 51 are in mesh with and actuated by two other bevel-gears 54 55, and the bevel-gears last mentioned are provided with clutch members 56 57, having preferably the form of annular beads integral therewith. Clutch members 58 59, mating the clutch members 56 57, are splined upon shafts 72 73 and are connected by forks 60 61 with a single rocking beam 62, which is journaled at 63 and is provided with I-bolts 64 65. Connected with the I-bolts 64 65 and depending therefrom are pull-cords 66 67, which pass through apertures 68 69 in the carriage 25, so as to be pulled by hand for the purpose of rocking the beam 62 in either of two directions, as desired. An electric lamp 70 is provided with a handle 71, whereby it may be lighted or extinguished at will. Two vertical shafts 72 73 are provided, respectively, with collars 72^a 73^a, mounted rigidly thereupon and serving to maintain the clutch members 58 59 clear of the clutch members 56 57 when out of operative engagement therewith, as indicated at the right of Fig. 3. A T-frame 74 partially supports the shafts 72 73, as indicated in said figure. Connected with the respective shafts 72 73 are worm-gears 75 76. Frame members 77, 78, and 79 are connected with the T-frame 74 and serve to support the journal or stub-shaft 63, upon which the beam 62 rocks, as above described. A sleeve 80 is rigidly connected with the T-frame 74 and encircles the shaft 45. A revoluble worm 81 meshes with the worm-gears 75 76. The feed-wires are shown at 82 83, the wire 82 being provided with a switch 84 and connected with the trolley-conductor 23. The trolley-conductor 22 is connected directly with the field-wire 83. A wire 85 is in communication with the trolleys 46 47 and with the lamp 70. A switch 86 is in communication with the wire 85 and with the two trolleys, so that when the switch 86 is closed the current passes through the lamp 70. (See diagrammatic view Fig. 5.)

The operation of my device is as follows: The switch 84 being closed, the following main circuit is completed: wire 82, conductor 23, trolley-wheel 47^a, trolley 47, motor 37, trolley 46, and trolley-wheel 46^a to field-wire 83. If the switch 86 be also closed, the circuit is the same as that just described, with the exception that a portion of the current passes in parallel through the wire 85 and the lamp 70, causing the lighting of the lamp. The motor 37 being thus energized is started into action and communicates motion to the revoluble shaft 45. This causes the revolution of the fan members 33, 34, 43, and 43^a. The motion of the shaft 45 causes the worm 81 to rotate, and this causes the gears 75 and 76 to rotate in opposite directions. These gears, acting alternately through the shafts 72 73, bevel-gears 54 55, and bevel-gears 50 51, cause the track-wheels 48 49 to rotate in a common direction. The track-wheels 48 49 thus serve as motor-wheels and by their engagement with the track causes the carriage to be shifted bodily from its starting position to one end of the track. One of the cam-plates 11^b 11^a is now engaged by the rocking lever 62, (see Fig. 3,) which is thus caused to rock. The rocking movement disconnects one of the clutch members—say 58—from its mate 56 and causes the other—say 59—to make engagement with its mate 57. The direction of rotation of the shaft 45 and the motion of the gear is never reversed; but the engagement and disengagement of the clutch members as just described causes one of the bevel-gears—say 57—to run idle, and the other—say 55—to act as a driving member. One of the bevel-gears is always idle, as only one track-wheel is driven for each direction of movement of the carriage. The result is that when the carriage reaches one end of the track it reverses and travels back to the opposite end of the track, where the other cam—say 11^b—again actuates the rocking lever 62, thereby causing the engagement and disengagement of the clutch members 58 59 with their respective mates 56 57, so as to start the track-wheels 48 49 to turn in a contrary direction. This of course causes the carriage to travel in the opposite direction, this motion being kept up indefinitely. The net result is that the carriage travels back and forth incessantly, and while the fans are always in action and each turns in its own peculiar direction the shifting of the carriage enables the fans to send air-currents in such directions as to prevent the formation of drafts.

Having thus described my invention, I claim as new and desire to secure by Letters Patent—

1. The combination of a traveling carriage, fan mechanism mounted thereupon, an electric motor mounted upon said carriage for propelling said fan mechanism, trolleys for feeding an electric current to said electric motor, track-wheels connected with said carriage for supporting the same, mechanism for connecting said track-wheels with said electric motor, and manually-operated mechanism for reversing the direction of said track-wheels relatively to said electric motor.
2. The combination of a carriage, motor mechanism mounted thereupon, a fan member connected with said motor mechanism and actuated thereby, the movement of said fan being always in the same direction, gearing connected with said motor mechanism, track-wheels connected with said gearing for

the purpose of propelling said carriage bodily along said track, and means controllable at will for reversing the direction of rotation of the track-wheels.

- 5 3. The combination of a track, a carriage mounted thereupon and provided with motor-wheels engaging said track, motor mechanism mounted upon said carriage and adapted to cause said motor-wheels to turn for the purpose of propelling said carriage, a revolute fan connected with said motor mechanism and driven directly thereby, and means for reversing the direction of rotation of said motor-wheels without affecting the direction of rotation of said revolute fan.
- 10 4. The combination of a track, a carriage provided with wheels engaging said track, said carriage being adapted to travel bodily in relation to said track, a fan member mounted upon said carriage and adapted to turn, mechanism common to said wheels and said fan member for propelling the same, and separate clutches operated automatically by the movements of said carriage for reversing the direction of travel thereof.
- 15 5. The combination of a carriage, an electric motor mounted thereupon, a revolute fan mounted upon said carriage and adapted to be actuated by said motor, a revolute shaft for connecting said motor with said fan, a worm mounted upon said shaft, worm-gears meshing with said worm and driven thereby, shafts connected with said worm-gears and actuated by movements of the
- 20 same, motor-wheels mounted upon said carriage for supporting the same and adapted to
- 25

be actuated alternately, clutch members connecting said motor-wheels with said revolute shafts and adapted to act alternately so that only one of said motor-wheels is driven at a time, a track for supporting said motor-wheels, and means for actuating said clutches.

6. The combination of a track, a carriage provided with wheels and adapted to run upon said track, electric motor mechanism mounted upon said carriage and adapted to turn said wheels, a plurality of trolley-conductors disposed underneath said track and supported thereby, a plurality of trolleys engaging said trolley-conductors, and connected with said electric motor mechanism for energizing the same, and a fan connected with said motor mechanism and actuated thereby.

7. The combination of a track, a carriage provided with wheels and mounted to run thereupon, motor mechanism mounted upon said carriage for propelling said wheels, gearing connecting said motor mechanism with said wheels, clutch mechanism mounted upon said carriage and adapted to reverse the direction of rotation of said wheels, and cam-plates mounted at opposite ends of said track for actuating said clutch mechanism.

In testimony whereof I have signed my name to this specification in the presence of two subscribing witnesses.
